UNITED STATES PATENT OFFICE

160,673

BELT BUCKLE OR SIMILAR ARTICLE

George A. Thoresen, Providence, R. I., assignor
to The Robbins Company, Attleboro, Mass., a
corporation of Massachusetts

Application May 3, 1950, Serial No. 9,677

Term of patent 7 years

(Cl. D17—1)

To all whom it may concern:

Be it known that I, George A. Thoresen, a citizen of the United States, residing in the city of Providence, county of Providence, and State of Rhode Island, have invented a new, original, and ornamental Design for Belt Buckle or Similar Article, of which the following is a specification, reference being had to the accompanying drawing, forming a part thereof.

Fig. 1 is a front elevational view of a belt buckle, embodying my new design; and

Fig. 2 is an edge view thereof.

I claim:

The ornamental design for a belt buckle or similar article, substantially as shown.

GEORGE A. THORESEN.
